DESIGN FOR A BATHING BAG

Vitalis Nachmias, New York, N. Y.

Application February 24, 1941, Serial No. 99,196

Term of patent 7 years

To all whom it may concern:

Be it known that I, Vitalis Nachmias, a citizen of Bulgaria, residing at 62 William Street, New York, N. Y., in the county of New York and State of New York, have invented a new, original, and ornamental Design for a Bathing Bag, of which the following is a specification, reference being had to the accompanying drawing, forming part thereof.

Fig. 1 is a side elevational view of a bathing bag embodying my new design and
Fig. 2 is an end view thereof in perspective.

The other side and end of the bag, not shown in the drawing, are like the side and end shown.

I claim:

The ornamental design for a bathing bag substantially as shown and described.

VITALIS NACHMIAS.
